US0D1037172S

(12) **United States Design Patent** (10) **Patent No.:** **US D1,037,172 S**
(45) **Date of Patent:** **** Jul. 30, 2024**

(54) **CONNECTOR**

(71) Applicant: **Japan Aviation Electronics Industry, Limited**, Tokyo (JP)

(72) Inventor: **Shin Kan**, Tokyo (JP)

(73) Assignee: **Japan Aviation Electronics Industry, Limited**, Tokyo (JP)

(**) Term: **15 Years**

(21) Appl. No.: **29/854,607**

(22) Filed: **Sep. 27, 2022**

(30) **Foreign Application Priority Data**

Apr. 12, 2022 (JP) ..... 2022-007972 D

CLAIM

The ornamental design for a connector, as shown and described.

DESCRIPTION

FIG. 1 is a front elevational view of a connector showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right and bottom side thereof; and,

FIG. 10 is a perspective view showing a rear, left and top side thereof.

The broken line showing of the connector is for the purpose of illustrating portions of the article and forms no part of the claimed design.

1 Claim, 7 Drawing Sheets
